UNITED STATES PATENT OFFICE.

HANS NYFFENEGGER, OF ZURICH, SWITZERLAND, ASSIGNOR TO THE FIRM OF AKTIENGESELLSCHAFT DER MASCHINENFABRIKEN ESCHER WYSS & CIE., OF ZURICH, SWITZERLAND.

STEAM-TURBINE INSTALLATION.

Application filed April 29, 1925. Serial No. 26,706.

To all whom it may concern:

Be it known that I, HANS NYFFENEGGER, a citizen of the Swiss Republic, residing at Zurich, Switzerland, have invented an Improvement in Steam-Turbine Installations, of which the following description, in connection with the accompanying drawings, is a specification, like characters on the drawings representing like parts.

10 This invention relates to improvements in steam-turbine installations in which a pre-heating of the feed-water in several steps is effected by means of bleeder steam.

15 It is a known fact that the step by step preheating of the feed-water by means of steam tapped from different stages of a turbine of a steam power installation involves an increased economy of the installation, as the tapped steam after having performed 20 mechanical work, delivers the greater part of its evaporation heat to the feed-water, so that its latent heat is recovered. The tapping of steam from a turbine requires however a turbine casing of a special design, and 25 the initial cost of the latter is therefore considerably raised if steam has to be tapped from several stages. A further disadvantage of tappings at several places, particularly with transversely arranged turbines on locomotives, is that it increases the 30 axial length of the turbine, so that owing to the limitations imposed by the railway clearance gauge, such a turbine could in many cases not be employed on locomotives.

35 According to the present invention, the tapping of the steam required for preheating the feed-water is effected at one single place only. This steam flows in conduits which are arranged in parallel to the different stages of the feed-water heater and in these conduits appliances utilizing different heat drops are interposed at least in those conduits which lead the bleeder steam to the initial and subsequent preheater stages up 45 to the second last stage.

The application of the invention to installations having a turbine with more than one casing and a reheater interposed between two such turbine casings affords besides a simplification of the design of the turbine casings thermodynamical advantages if the tapping is made from the connection joining the first turbine casing to the intermediate re-heater. In this case the in-

termediate re-heater is substantially relieved 55 and too highly superheated steam does not flow to the preheater stages, as would otherwise occur when multiple tappings are employed and in which case the tapped steam cannot then be fully utilized in the stages of 60 the preheater since the saturation temperature determines the limit to which preheating can be effected.

Illustrations of the subject matter of the present invention are given on the accompanying drawings in which:

Fig. 1 shows a steam-turbine installation, in which the steam for heating the preheaters is bled from one point of the main turbine,

Fig. 2 shows a twin casing steam-turbine 70 installation, in which the steam for heating purposes is bled from a point between the two casings,

Figs. 3 and 4 show detail modifications.

In the installation illustrated in Fig. 1, 75 1 denotes the boiler, 2 a superheater and 3 the main turbine of the installation. A branch 6 is provided for extracting the steam for heating purposes required in a feed-water heater 7 having three stages. 80 The tapped steam flows to the three stages of the preheater 7 by three conduits 8, 9 and 10 arranged in parallel, of which the conduit 8 is connected to the lowest stage of the preheater and the conduit 10 leads to 85 the highest stage of the preheater. In the conduit 8 an auxiliary turbine 11 is inserted and an auxiliary turbine 12 is inserted in the conduit 9. The turbine 11 operates with a higher expansion ratio than the auxiliary 90 turbine 12. 13 denotes the condenser of the main turbine 3, and 14 is a centrifugal condensate pump drawing the condensate from the condenser 13 via the conduit 16 and delivering it into the feed-water heater 7 from 95 which the preheated feed-water flows through the conduit 15 into the boiler 1.

With the above described installation of the tapping of the steam utilized for pre-heating purposes in the various stages of 100 the preheater 7 occurs at the single place 6.

Fig. 2 shows an installation in which the main turbine is designed as a twin-casing turbine; 3 is the high-pressure part and 4 the low-pressure part. 2 is again a superheater and 5 denotes an intermediate re-heater placed between the high pressure part 3 and the low pressure part 4. The

steam for heating purposes is tapped from a point 6', situated between the high pressure part 3 and the re-heater 5. In other respects this installation is identical to that described above.

The connection branch for bleeding the steam can be situated at any suitable point on the main turbine whether single or multiple casings are employed. When the main 10 turbine is designed with a multi-casing, the point of tapping may be arranged at the exhaust trunk of one of the turbine casings as is indicated at 17 in Fig. 3.

Instead of the auxiliary turbines 11 and 15 12, obviously other appliances requiring heat such as steam engines, steam hammers, installations for evaporating and heating purposes, may be inserted in the conduits 8 and 9 arranged in parallel. The number of 20 the conduits arranged in parallel and of the stages of the feed-water heater does not influence the scope of the invention. Further it may be mentioned that a steam power engine 18 or another appliance requiring heat 25 may also be inserted in the conduit 10 leading to the highest stage of the feed-water heater 7 as is shown in Fig. 4.

I claim:

1. A steam-turbine installation, including 30 in combination a feed-water heater having several stages and adapted to be heated by steam-tapped at a single point on the turbine installation, conduits arranged in parallel and leading said tapped steam to the stages of said feed-water heater, and appliances requiring heat adapted to utilize different heat drops and interposed at least in those of said conduits which lead the 35 bleeder steam to the initial and subsequent preheater stages up to the second last stage.

2. A steam-turbine installation, including 40 in combination a feed-water heater having several stages, means to tap steam from said turbine installation at one point only, conduits arranged in parallel and leading said 45 tapped steam to the stages of said feed-water heater, and appliances requiring heat oper-

ating under different heat drops and inserted in said conduits.

3. A steam-turbine installation, including 50 in combination, a multi-casing turbine, a feed-water heater having several stages, an intermediate re-heater situated between two of the turbine casings, means to tap steam at a point in front of the re-heater, conduits arranged in parallel and leading said tapped steam to the stages of said feed-water heater, and appliances requiring heat operating under different heat drops and inserted in said conduits.

4. A steam-turbine installation, including 55 in combination, a feed-water heater having several stages, means to tap steam from said turbine installation at one point only, conduits arranged in parallel and leading said tapped steam to the stages of said feed-water heater, and steam power engines operating with different expansion ratios inserted in said conduits.

5. A steam-turbine installation, including 60 in combination a main turbine, a feed-water heater having several stages, means to tap steam from said main turbine at one point only, conduits arranged in parallel and leading said tapped steam to the stages of said 65 feed-water heater, and steam turbines operating with different expansion ratios inserted in said conduits.

6. A steam-turbine, installation, including 70 in combination a multi-casing turbine, 80 a feed-water heater having several stages, an intermediate re-heater interposed between two of the casings of the turbine, means to tap steam from said turbine installation at a point in front of the re-heater, conduits arranged in parallel and leading said tapped steam to the stages of 85 said feed-water heater, and steam turbines operating with different expansion ratios inserted in said conduits.

In testimony whereof, I have signed my name to this specification.

HANS NYFFENEGGER.
